(57) **CLAIM**

The ornamental design for a railed gas tube as shown and described.

DESCRIPTION

FIG. 1 is a top perspective view of the railed gas tube;

FIG. 2 is a front view of the railed gas tube;

FIG. 3 is a back view of the railed gas tube;

FIG. 4 is a right side view of the railed gas tube;

FIG. 5 is a left side view of the railed gas tube;

FIG. 6 is a top view of the railed gas tube; and,

FIG. 7 is a top view of the railed gas tube.

The broken lines in the drawings disclose the unclaimed portions of the railed gas tube only and form no part of the claimed design.
